(57) **CLAIM**

The ornamental design for a decorative band for a kitchen mixer, as shown and described.

DESCRIPTION

FIG. 1 is a front view of the decorative band for a kitchen mixer showing the new design;

FIG. 2 is a back view thereof;

FIG. 3 is a top view thereof;

FIG. 4 is a bottom view thereof;

FIG. 5 is a left side view thereof, with the right side view being identical; and,

FIG. 6 is a perspective view of the decorative band on a kitchen mixer.

The portions shown in broken lines are not part of the claimed design.

1 Claim, 2 Drawing Sheets
